(57) **CLAIM**

The ornamental design for the tooth clamp, as shown and described.

DESCRIPTION

FIG. 1 is a perspective view of an exemplary embodiment of a tooth clamp according to the present invention;

FIG. 2 is a right side view of the tooth clamp of FIG. 1, the left side being a mirror image thereof;

FIG. 3 is a top view of the tooth clamp of FIG. 1;

FIG. 4 is a bottom view of the tooth clamp of FIG. 1;

FIG. 5 is front view of the tooth clamp of FIG. 1;

FIG. 6 is rear view of the tooth clamp of FIG. 1;

FIG. 7 is a perspective view of an alternate exemplary embodiment of a tooth clamp according to the present invention;

FIG. 8 is a right side view of the tooth clamp of FIG. 7, the left side being a mirror image thereof;

FIG. 9 is a top view of the tooth clamp of FIG. 7;

FIG. 10 is a bottom view of the tooth clamp of FIG. 7;

FIG. 11 is front view of the tooth clamp of FIG. 7; and,

FIG. 12 is rear view of the tooth clamp of FIG. 7.
